(57) **CLAIM**

The ornamental design for a collaborative workspace, as shown and described.

DESCRIPTION

FIG. 1 is a perspective view embodying the inventive design;

FIG. 2 is a front view thereof;

FIG. 3 is a left view thereof;

FIG. 4 is a rear view thereof;

FIG. 5 is a top view thereof;

FIG. 6 is a bottom view thereof;

FIG. 7 is a perspective view of a second embodiment of the inventive design;

FIG. 8 is a front view of FIG. 7;

FIG. 9 is a left view of FIG. 7;

FIG. 10 is a rear view of FIG. 7;

FIG. 11 is a top view of FIG. 7; and,

FIG. 12 is a bottom view of FIG. 7.

The broken lines are directed to environment and form no part of the claimed design.

1 Claim, 12 Drawing Sheets(56)
